CLAIM

The ornamental design for an adjusting button of a tape dispenser, as shown and described.

DESCRIPTION

FIG. 1 is a perspective view of the adjusting button of a tape dispenser showing my new design;

FIG. 2 is a front view thereof;

FIG. 3 is a rear view thereof;

FIG. 4 is a top view thereof;

FIG. 5 is a right side view thereof, the left side view being a mirror image thereof;

FIG. 6 is a side view of a tape dispenser including the adjusting button, the broken line structure forming no part of the claimed invention; and,

FIG. 7 is a perspective view of the tape dispenser including the adjusting button, the broken line structure forming no part of the claimed invention.
